[57] CLAIM

The ornamental design for a control panel for a microfilmer, as shown and described.

DESCRIPTION

FIG. 1 is a top plan view of a control panel for a microfilmer showing my new design;
FIG. 2 is a right side elevational view;
FIG. 3 is a left side elevational view;
FIG. 4 is a front elevational view;
FIG. 5 is a rear elevational view;
FIG. 6 is a right, front and top perspective view thereof.
The broken line showings of the underneath structure in FIGS. 2-5 are environmental only and form no part of the claimed design.

FIG. 1

FIG. 2

FIG. 4

FIG. 3

FIG. 5

FIG. 6
